UNITED STATES PATENT OFFICE

WILLIAM RAMSAY, OF DUNFERMLINE, SCOTLAND, ASSIGNOR TO GOLDING BROS. COMPANY, OF NEW YORK, N. Y., A CORPORATION OF NEW YORK

DESIGN FOR A TEXTILE FABRIC OR SIMILAR ARTICLE OF MANUFACTURE

Application filed March 19, 1930. Serial No. 34,967. Term of patent 3½ years.

To all whom it may concern:

Be it known that I, WILLIAM RAMSAY, a subject of the King of Great Britain, and a resident of Dunfermline, Fifeshire, Scotland, have invented the new, original, and ornamental Design for a Textile Fabric or Similar Article of Manufacture, of which the following is a specification.

Reference is had to the accompanying drawing, in which the figure is a plan view of a textile fabric or similar article showing one-half of the design, the remaining half being a reversed repetition thereof.

I claim:

The ornamental design for a textile fabric or similar article of manufacture substantially as shown and described.

WILLIAM RAMSAY.
